UNITED STATES PATENT OFFICE.

PHILIP W. PULIG, OF PHILADELPHIA, PENNSYLVANIA.

MOTOR-METER-ILLUMINATING DEVICE.

Application filed June 21, 1922. Serial No. 569,959.

To all whom it may concern:

Be it known that I, PHILIP W. PULIG, a citizen of the United States, residing at 1218 North Frazier Street, in the city and county of Philadelphia, State of Pennsylvania, have invented a new and useful Motor-Meter-Illuminating Device, of which the following is a specification.

This invention relates to motor meter illuminating devices and it has more particular reference to the type or form of device embodying means for attachment to the filler connection of automobile radiators, said means being of a nature and character for illuminating the motor meter proper, so that it can be seen at all times, that is to say it may be clearly observed when the car on which my device is installed is used after dark.

20 The primary object of my invention is to provide a device of the foregoing referred to character which is applicable to any of the standard forms of motor meters without in any way affecting their usefulness, while 25 at the same time the illuminating device is so mounted relative thereto that it can be directed in any desired manner thereon.

Another object of this invention is to provide a device of the kind referred to which 30 is fitted with a removable lamp the same being of a character and form which readily lends itself for easy removal for use when inspecting or repairing any part of the car.

Further objects of this invention reside in 35 the provision of a motor meter illuminating device which is simple in construction, cheap to manufacture, easy to install, and very effective for the purposes for which it has been devised.

40 With the foregoing and other objects in view, as will be more apparent from the following description, this invention consists essentially in the novel features of construction, combinations and arrangements of 45 parts hereinafter fully described and more specifically defined by the appended claim.

In the further disclosure of the invention reference is to be had to the accompanying sheet of drawings constituting a part of 50 this specification and in which like charac-

ters of reference designate the same or corresponding parts in all the views.

Figure 1 is a side elevation of my improved motor meter illuminating device; and

55 Figure 2 is a front elevation of the same.

Referring more particularly to the views I construct an arm or bracket 3 of suitable material from flat sheet metal and fashion the same with an eye-piece 4, which is of appropriate dimensions to fit snugly about the shank of a motor meter 5 and between the filler cap 6 and collar 7 of said motor meter. It will, of course, be obvious that this arm or bracket 3 may be of straight formation in longitudinal section or provided with an upwardly indented portion 8 as shown for passage over the knurled lock nut 9 of a hinged filler radiator cap, but I wish it clearly understood that I do not confine myself to the form shown as it will be obvious the same is susceptible of variation to accommodate my invention to different types of radiator fillers.

65 In applying my invention as shown it will be obvious that the lamp or illuminating device is in the form of a three piece metal structure which is attached to the motor meter 5 or other radiator cap novelty, said lamp or illuminating device 10 being supported by the arm or bracket 3 between the top of the radiator or filler cap 6 and the lowest exposed part of the motor meter 5 or other radiator novelty, thereby providing 70 a novel means for supporting or securing the 75 lamp or illuminating device 10 firmly in place when attached in place.

80 In the construction of the lamp or illuminating device 10 I employ the arm or bracket 3 one end whereof is directed toward the lower back of the car or automobile and disposed parallel with the engine hood 11 thereof, said arm or bracket being fashioned as above stated with an eye-piece 4 through which is passed the post or shank of the 85 motor meter 5 or other radiator novelty. This washer like or eye-piece construction 4 is also devised to provide an effective means for keeping any steam from escaping from the radiator 12 between the top or cap 6 100

thereof and the lowest exposed portion of the motor meter 5 or other radiator novelty.

It will, of course, be understood that the hump or indented portion 8 of the arm or bracket 3 has been provided in order to allow for a clearance to the left or right hand when moving the lamp or illuminating device 10 to avoid the thumb screw or lock nut 9 which is to be found in certain radiator wing caps 10 at present in use.

Referring once again to the arm or bracket 3, the entire outer end 13 of the arm or bracket 3 is also of washer like or eye-piece construction and it is fitted with a swivel 16 pin or rivet 14 that couples thereto a bifurcated or stirrup-shaped bearing 15, which has a rearward inclination, as shown. This bifurcated or stirrup-shaped bracket 15 is disposed substantially at right angles or 20 perpendicular to the aforesaid arm or bracket 3 but it is to be noted that the rearward contour thereof is provided to allow a clearance between the bottom of the lamp or illuminating device 10 and the bottom 25 of the bifurcated or stirrup-shaped bracket 15 when it is desired to raise or lower said lamp or illuminating device 10. The upper or free ends of the bifurcated or stirrup-shaped bracket 15 are slotted or 30 forked at 16 to provide trunnions for the reception of screw bearings 17 on the body of the lamp or illuminating device 10 whereby the latter may be easily removed when locating trouble or making repairs.

Referring now more in detail to the lamp or illuminating device 10, it will be observed that the same is of tubular formation; that is to say it comprises a main or body portion 18 with the front or forward end inwardly flared or shrouded to firmly grip and securely hold in place the lens 19. It will, of course, be clearly understood that the thumb screws or bearings 17 serve to adjust and lock the lamp or illuminating device 10 45 at any desired angular inclination for the purpose of directing the beam of light therefrom as required. The rear of the main or body portion 18 may be screw threaded for a short distance at 20 for the reception of a concavo-convex or hemispherical end cover or cap 21 that provides access to the interior thereof when desired.

Fitting snugly to the bottom rear end of the aforesaid main or body portion 18 is a small plug or socket connection 22 that provides for an ordinary electric connection 23 of any of the well known types.

Attached to the front end of the main or body portion 18 is a small block 24 or piece 50 of suitable material having attached thereto a length of spring steel 25 the free end whereof is appropriately fashioned into a headed or gripping part 26 or hood-like portion which serves when the lamp 10 is disconnected to securely hold the same in any

desired position on the car when inspecting a trouble condition or looking after a repair.

The aforesaid lens 19 having one side or face convex and the other side flat and being of slightly less diameter than the main or body portion 18, provides a seat for the larger or outer end of a truncated reflector 27 that is preferably made of a highly lustrous material, so as to give a maximum reflective efficiency. Fitting on the smaller 70 end of the aforesaid reflector 27 is a fiber washer 28 which is fashioned with a cutaway bore 29 that allows for the free entry of the electric wires 30. The front of the aforesaid washer 28 rests snugly against the rear end 75 of the plug socket 22 in the bottom of the main or body portion 18 and also against two small stays 31 in the bulb socket 32, thereby keeping the reflector 27 firmly in place.

An ordinary bulb 33 of say two candle power double contact with wires 30 entering the same at a point near the rear thereof and fastened in place by two screws 34 provided for the purpose at the extreme 80 rear thereof. Two short wires running from the plug socket 22 through the fiber washer 28 connect with the bulb socket 32 as shown. An ordinary double contact plug 35 provides the means of insuring electric contact and convenience when it is desired to disconnect the light 33 in order to remove the radiator or filler cap 6, or to raise the engine hood 11; and, as will be perfectly clear to those conversant with the art, the entire lamp or illuminating device can be moved either to the right or left hand without disconnecting the plug 35.

An ordinary double contact connection being used from the plug 35 and leading 105 through a hole 36 in the hood 11, preferably where the hood and radiator join, leaves a small length of wire that allows for clearance, and in this connection I provide a male and female coupling device so that ready 110 connection and disconnection can be effected.

Obviously the lighting or illuminating device 10 will be controlled from an appropriate switch on the dash of the machine, and while there has been shown and described one practical embodiment of my invention, the same is not to be conservatively construed, as it will be obvious that many detail changes may be effected without in any way departing from the true spirit and scope thereof. The right is, therefore, hereby reserved to make such changes and variations as fairly lie within the scope of the appended claim.

Having described my invention what I 120 claim as new and desire to secure by Letters Patent is:—

A motormeter lamp for automobiles comprising in combination with a motormeter, a horizontally disposed support having an 125

aperture at one end thereof for pivotal attachment to the motormeter, a bifurcated bracket pivotally mounted on the other end of said support, the said bracket comprising rearwardly inclined arms having slotted portions at the upper ends thereof, screw clamp bearings carried by the lamp and adapted to be received into said slots for adjustably po-

sitioning the lamp with respect to the support, and a J-shaped spring having one end thereof fixed to one end of the lamp and the other end embracing the other end of the lamp to enable the lamp to be supported from some other support when the lamp is removed from the bifurcated bracket.

PHILIP W. PULIG.
